519.

John Thonson
Letter Patent

The Schedule referred to in this Letter Patent and making part of the same containing a description in the words of the said John Thonson himself of his Improvement on the & water tight roofs covered with tin or any other metallic substance

To all to whom these presents shall come. Be it known that I John Thonson of Lexington, Va. in the County of Rockbridge & State of Virginia have invented certain new improvements on the Late patent obtained by C. Bonnycastle for constructing roofs covered with tin & other metals. I have invented sundry tools & machinery for performing the work & that the following is a full & exact description of my improvement on the Bonnycastle patent & on the tools & machinery used to do the work which my improvements tools & machinery were invented and improved by me. Fig. 1. Represents a double lock sprung circular comb on the top of the roof (in place of the small solars above which units the heads on the Bonnycastle roof) which is a perfect security against leakage & makes a more consistent & substantial finish to the work. It is constructed in the following manner, edges of one inch deep are laid off on the upper range of the tin or metal that the roof is covered with on each side to exclude in opposite directions. Strips of tin are introduced between to cover nail the covering at top. Then follows a flat sprung cap secured by cramps let into the same. Over the whole is sprung a large circular tube to prevent any water entering under the covering. Fig. 2. Represents the different small sheet of iron made lengthways by half inch grooves making as it were one continuous sheet from the eaves to the top of the comb or cap so as to cover the necessity of lapping the sheet as on the Bonnycastle plan & thereby making the work perfectly water tight & leaving the sheet free for expansion & contraction which will naturally take place when the tin is on one large continuous sheet and has no room to play in the joints. When the iron is not in contact with sheet shows a surface to the weather when on the roof.

John Thonson

of 9 by 12 inches & no more required to make the same. Figure 3 Represents an improved mode of making the gutter at the one showing how it is secured to the rafters or planks under the eaves without the aid of iron spikes or copper straps to secure it to the roof, thereby preventing the injury such spikes & straps create by passing through the timber also securing any drift of water that comes from the roof & preventing any passing between the gutter & cornice. When it will be observed the heads on the eaves are extended to the heads on the front of the gutter as a strong support to it. The circular part of the gutter is made 11 inches, the part that lays on the cornice 4 inches the model will further explain. Figure 4 Represents one side of the model covered so as to be fire proof on both sides. The rafters being made of rich & half pine plank by 4 $\frac{1}{2}$ an half inches deep & let into a circular beam at top & cornice plate below when over 10 or 12 feet long transverse pieces are let in of 3 inches deep. These rafters stand 11 inches apart from each other & the air is stretched over & the joints lock on the centre of the rafter. The whole of this forms to support the tiled covered with sheet tin, no sheathing plank is used. & the roof constructed in this way is perfectly watertight & fire proof in both sides affording freedom an intermediate entrance with their hose when it is necessary to introduce it this the roof. Figure 5 Represents a machine to make the side & end edges on the tin with certain improvements on it in the form of an open butt hinge. Model will explain to form the base that suits the joints to the roof. Figure 6 Represents a machine made of plank & sheet iron to make the heads in joints of 6 feet long. Plank 6 feet long & $\frac{1}{2}$ an inch wide a species of iron with edges to hold the base during the soldering. The model will explain. Fig. 7. Represents a lot of chain ladders made of plank to serve as scaffolds to put on a roof. The ladders are 6 feet long & inches wide. 3 hooks of iron made thus & arranged to enter between the joints on the straight plank to take the appearance of each of the other top corners of the ladders. 3 & hooks this are inserted so that a chain of two does not take weight any straight iron in any order to be connected together to form a strong & tight scaffolds.
